CLAIM

The ornamental design for components of a reverse osmosis water filtration system as shown and described.

DESCRIPTION

FIG. 1 is a perspective view of an embodiment showing the new design for components of a reverse osmosis water filtration system;

FIG. 2 is a front view of the components of FIG. 1;

FIG. 3 is a rear view of the components of FIG. 1;

FIG. 4 is a left view of the components of FIG. 1;

FIG. 5 is a right view of the components of FIG. 1;

FIG. 6 is a top view of the components of FIG. 1;

FIG. 7 is a bottom view of the components of FIG. 1;

FIG. 8 is a perspective view of another embodiment showing the new design for components of a reverse osmosis water filtration system;

FIG. 9 is a front view of the components of FIG. 8;

FIG. 10 is a rear view of the components of FIG. 8;

FIG. 11 is a left view of the components of FIG. 8;

FIG. 12 is a right view of the components of FIG. 8;

FIG. 13 is a top view of the components of FIG. 8; and

FIG. 14 is a bottom view of the components of FIG. 8.

FIG. 15 is a perspective view of another embodiment showing the new design for components of a reverse osmosis water filtration system;

FIG. 16 is a front view of the components of FIG. 15;

FIG. 17 is a rear view of the components of FIG. 15;

FIG. 18 is a left view of the components of FIG. 15;

FIG. 19 is a right view of the components of FIG. 15;

FIG. 20 is a top view of the components of FIG. 15; and

FIG. 21 is a bottom view of the components of FIG. 15.

FIG. 22 is a perspective view of another embodiment showing the new design for components of a reverse osmosis water filtration system;

FIG. 23 is a front view of the components of FIG. 22;

FIG. 24 is a rear view of the components of FIG. 22;

FIG. 25 is a left view of the components of FIG. 22;

FIG. 26 is a right view of the components of FIG. 22;

FIG. 27 is a top view of the components of FIG. 22; and,

FIG. 28 is a bottom view of the components of FIG. 22.

(Continued)

The portions of the components of a reverse osmosis water filtration system in FIGS. 1-28 shown in broken lines are included to show features that form no part of the claimed design.
